UNITED STATES PATENT OFFICE

BUTLER J. MASKINS, OF CHICAGO, ILLINOIS, ASSIGNOR TO JOSEPH WEIDENHOFF, INC.,
OF CHICAGO, ILLINOIS, A CORPORATION OF ILLINOIS

VISE FOR CENTERING GENERATORS AND THE LIKE

Application filed May 31, 1930. Serial No. 458,184.

This invention relates to a vise for centering cylindrical objects, and is adapted particularly for use in connection with a test bench for generators, motors, and the like, 5 wherein there is a shaft adapted to be brought substantially into alignment with the shaft of the generator to be tested.

An object of this invention is to provide a vise which will automatically bring a cylindrical object to be gripped into the horizontal plane of a part with which the cylindrical object is to co-operate while the vise jaw moves at an angle to the horizontal. In the case of a generator, motor, or the like, it 10 co-operates with a drive means having a clutch for connection to the generator shaft.

Another object is to provide a vise of this type which permits free access to the top of the generator being gripped thereby.

Another object is to provide a vise which has four jaws, two of which are out of the horizontal plane.

Another object is to provide means including one of the movable jaws for gripping rectangular objects, such as magnetos, which are to be centered with respect to some of the mechanism.

These and other objects, as will hereinafter appear, are accomplished by this invention, 20 which is fully described in the following specification, and shown in the accompanying drawings, in which—

Figure 1 is a side elevation of a vise embodying the invention;

Fig. 2 is a partial enlarged section on the line 2—2 of Fig. 1;

Fig. 3 is a longitudinal section on the line 3 of Fig. 2; and

Fig. 4 is a partial view similar to Fig. 1 showing the vise gripping a magneto.

The embodiment illustrated comprises a vise having a frame 10 extending over and adapted to rest upon guide rails 11 and 12 which are supported at their ends upon supports 13 and 14, which in turn rest upon a top plane surface 15 of a test bench, or the like. This test bench is provided with a shaft (not shown) but which carries a chuck 16, which is driven from a suitable source of power (not 45 shown).

One or more bars 17 lie beneath the rails 11 and 12, and are adjustably carried on the frame 10 by means of screws 18 and 19. By loosening these screws the vise may be moved both longitudinally and transversely with 55 relation to the chuck 16. Longitudinally channeled side bars or guides 20 are secured to lateral extensions on the frame 10 by means of screws or the like 21. The channeled portions of the guides 20 are turned inwardly so 60 as to face each other, and to serve as guides for a carriage 22 which has laterally extending pins 23 on which are journaled wheels 24 on one side and 25 on the other. The two wheels 24 on one side are spaced apart some 65 distance, as shown in Figs. 1 and 4, while the single wheel 25 on the opposite side is spaced substantially midway between them. As will later be seen this permits of a self-alignment of the gripping jaws on the cylindrical object to be held. 70

The wheels 24 and 25 are preferably beveled, as shown, and fit into similarly beveled grooves in the side rails 20. The carriage 22 is thus movable along the guides 20, which are 75 preferably set at an angle of substantially $22\frac{1}{2}^{\circ}$ to the horizontal leading upwardly and forwardly toward the opposite jaws 10^a and 10^b of the vise. The carriage itself has two jaws 26 which are spaced some distance 80 apart, as shown in Fig. 2, and which normally lie below the level of the plane passing through the center of the chuck 16.

Each of the jaws 26 has two jaw teeth 26^a and 26^b which are so placed as always to 85 include a cylindrical object between themselves and the opposing jaws 10^a and 10^b of the vise body. This is due to the fact that they are moved upwardly and forwardly on an angle of substantially $22\frac{1}{2}^{\circ}$, and also to 90 the fact that they are so moved along this $22\frac{1}{2}^{\circ}$ line that a point substantially midway between them moves along a straight line X—Y passing through the intersection of the horizontal line, through the center of 95 the cylinder A and the forward circumference of this cylinder. Three positions of the jaws 26 are indicated, showing them gripping cylinders A, A' and A² of different sizes.

A bar 27 extends across the rear end of the carriage 22 and passes through the end of a tube 28 which carries at the opposite end a nut 29, into which is threaded a screw 30 which has a reduced end 31 which passes through a block 32 which is hingedly mounted at 33 on the main frame 10. A hand wheel 34 is secured to the reduced portion 31. Thus it will be seen that as the hand wheel 34 is turned, the carriage 22 is moved back or forth.

The frame 10 has a projection 10^a in which is slidably mounted a screw 35 which is provided with a key and keyway 36 to prevent the screw from turning. The screw is threaded into a hand wheel 37 which is guided in a suitable opening 38 in the projection 10^b. The inner end of the screw 35 is provided with a channeled gripping end or jaws 39, which is adapted to make contact with a cylindrical object A, such as a generator, which is to be gripped in the vise.

Thus it will be seen that the jaws 26 may be moved back and forth to grip the generator A, and these will be sufficient to hold it for most purposes. If, however, it is so desired the jaws 39 can also be advanced so as to further grip the cylinder A, or the jaws 39 alone may be used.

Figure 4 shows the vise when used to grip a magneto B. For this purpose an adapter C is used which is of an L-shape in cross section, which is adapted to be gripped between the shoulder or tooth 26^b on the carriage 22 and the jaws 10^a of the frame 10. In this connection it will be noted that the vertical leg of the adapter C makes contact at the top with the upper portion of the jaws 10^a, and at the bottom with the vertical inner side of the frame 10. The magneto B is set loosely into the angle thus formed between the bottom and side of the adapter C, and the magneto is held in place by the gripping jaw 39. The adapter C is so formed as to bring the magneto shaft B' into alignment with the chuck 16 of Fig. 1, when the magneto B is thus gripped by the vise. The adapter C may take several forms, depending upon the magneto, or other object, with which it is intended to be used.

It will also be observed that the inner faces 10^a and 10^b are oppositely and equally inclined from the vertical so that when cylindrical objects, as A, are forced against them, these objects will be automatically centered with respect to a line through the chuck 16. It will be seen that when a cylindrical object is gripped between the surfaces 10^a and 10^b on the one side and the jaws 26^a and 26^b on the other, it will automatically be brought to the vertical level of the chuck 16.

Having thus gripped the generator, motor, magneto, or other object to be tested to a position wherein its shaft is at the level of the chuck 16, it is then necessary to adjust

the vise laterally so as to bring it into substantially the vertical plane of the chuck 16. This is done by loosening the screws 18 and 19, thereby permitting the frame 10 to be slid back and forth with respect to the guides 11 and 12 until the generator A or the magneto B is substantially in alignment with the chuck 16, so that the latter may grip its shaft. The screws 18 and 19 are then set so as to clamp the frame 10 of the vise firmly on the guides 11 and 12.

While I have shown and described but a few embodiments of my invention, it is to be understood that it is capable of many modifications. Changes, therefore, in the construction and arrangement may be made which do not depart from the spirit and scope of the invention as disclosed in the appended claims.

I claim:

1. A vise for centering cylindrical generators and the like comprising two fixed jaws substantially equally spaced on opposite sides of a given line, and a member having two rigid jaws movable at an angle to said line adapted to grip between themselves and the fixed jaws cylindrical objects of different sizes so that the centers of the various cylindrical objects all remain on the given line.

2. A vise for centering cylindrical generators and the like comprising two fixed jaws substantially equally spaced on opposite sides of a given line, and jaws movable at an angle to said line adapted to grip between themselves and the fixed jaws cylindrical objects of different sizes so that the centers of the various cylindrical objects all remain on the given line, a point midway between the movable jaws being movable along a line intersecting the cylinder substantially midway between the fixed jaws.

3. A vise for centering cylindrical generators and the like comprising two fixed jaws substantially equally spaced on opposite sides of a given line, and jaws movable at an angle of substantially 22½° to said line adapted to grip between themselves and the fixed jaws cylindrical objects of different sizes so that the centers of the various cylindrical objects all remain on the given line.

4. A vise for centering cylindrical generators and the like comprising two fixed jaws substantially equally spaced on opposite sides of a given line, and two other fixed jaws movable at an angle of substantially 22½° to said line adapted to grip between themselves and the first-mentioned fixed jaws cylindrical objects of different sizes so that the centers of the various cylindrical objects all remain on the given line, a point midway between the movable jaws being movable along a line passing substantially midway between the fixed jaws.

5. A vise for centering cylindrical generators and the like comprising two fixed jaws

substantially equally spaced on opposite sides of a given line, and jaws movable at an angle to said line adapted to grip between themselves and the fixed jaws cylindrical objects of different sizes so that the centers of the various cylindrical objects all remain on the given line, said movable jaws being located beneath the object to be gripped so as to have the top of the object accessible.

10 6. A vice for centering cylindrical generators and the like comprising two fixed jaws substantially equally spaced on opposite sides of a given line, jaws movable at an angle to said line adapted to grip between themselves and the fixed jaws cylindrical objects of different sizes so that the centers of the various cylindrical objects all remain on the given line, and another jaw substantially on the given line, lying between the movable jaws, 20 movable to grip an object between said jaws.

7. A vise for centering cylindrical generators and the like comprising two fixed jaws substantially equally spaced on opposite sides of a given line, and two other fixed jaws 25 movable at an angle to said line adapted to grip between themselves and the first-mentioned fixed jaws cylindrical objects of different sizes so that the centers of the various cylindrical objects all remain on the given line, said jaws having shoulders for gripping a rectangular object therebetween.

In testimony whereof, I have hereunto set my hand this 19th day of May, 1930.

BUTLER J. HASKINS.
